(57) **CLAIM**

The ornamental design for a low-profile light weight detachable seat for a walker as shown and described.

DESCRIPTION

FIG. 1 is an isometric view of low-profile light weight detachable seat for a walker showing our new design;

FIG. 2 is a front elevational view of FIG. 1;

FIG. 3 is a top plan view of FIG. 1;

FIG. 4 is a bottom plan view of FIG. 1;

FIG. 5 is a right elevational view of FIG. 1;

FIG. 6 is a left elevational view of FIG. 1;

FIG. 7 is a rear elevational view of FIG. 1;

FIG. 8 is an operational view in an environment of use of FIG. 1; and,

FIGS. 9, 10 and 11 are operational views in environment of use of FIG. 1.

The broken lines in the drawings depict portions of low-profile light weight detachable seat for a walker that form no part of the claimed design.
